UNITED STATES PATENT OFFICE

CLAUDE SIEBRING, OF GEORGE, IOWA

OIL-BURNING STOVE

Application filed June 7, 1929. Serial No. 369,083.

My invention relates to oil burning stoves of the type disclosed in my co-pending application, Serial No. 278,855, filed May 18, 1928, which has now matured into Patent No. 1,743,402, Jan. 14, 1930, and has for its object to simplify and improve upon said stove.

More particularly it is my object to provide in a stove of the type having a pair of upright flues and a winding combustion chamber connecting said flues at their lower ends, a more substantial bracing structure connecting the flues so that the stove as a whole is more rigid and solid in construction than previously.

15 A further object is to eliminate a number of parts previously considered necessary in supporting a fuel tank in such a manner as to discharge fuel from said tank into one of the flues without entirely cutting off the flow of air through said flue.

Another object is to provide a stove capable of supporting a tank of larger capacity than heretofore.

Another object is to provide a stove that 25 may be used either as a tank heater or as a brooder stove having certain features adapting it to both uses.

Another object is to provide a stove that is self-extinguishing in the event of an 30 excess flow of oil.

The foregoing objects are all solved in a structure embodying a combined brace and fuel tank structure connected to flues. Such an arrangement makes it possible to employ 35 portions of the flues as end walls for the tank; thus cutting down the amount of material necessary, makes it possible to make a direct connection between the tank and the inside of one of the flues below the top of the flues 40 for a drip valve, and gives a much stronger bracing construction than a simple brace would afford.

With these and other objects in view, my invention consists in the construction, arrangement and combination of the various 45 parts of my device, whereby the objects contemplated are attained, as hereinafter more fully set forth, pointed out in my claims, and illustrated in the accompanying drawings, in which:

Fig. 1 is a plan view of the stove.

Fig. 2 is a side elevation of the stove.

Fig. 3 is a sectional view taken longitudinally through the tank and adjacent flue portions and

55 Fig. 4 is a detail, sectional view taken through one of the flues.

Fig. 5 is a detail, sectional view of the drip valve.

Fig. 6 is a side elevation of the stove used 60 as a brooder.

I have used the reference character 10 to indicate generally the winding combustion chamber of the stove which is identical to that described in my co-pending application. 65 The two flues are indicated at 11 and 12, respectively, and the supporting legs 13 and 14 are similar in construction to that of my said patent.

The tank comprising the side walls 14, 70 joined to the sides of the flues 11 and 12 and the top and bottom walls 15 and 16, respectively, cut out to fit the curve of the flues 11 and 12 and joined thereto to form a completely enclosed tank. The method of joining the tank to the flues is by welding due to the heat to which the walls are subjected and the necessity for resisting said heat.

75 The walls of the flues 11 and 12 near the bottom of the tank are apertured to receive a pair of fuel delivery pipes 17 and 18, respectively, each having a threaded end upon which may be threaded the drip valve 19. When the drip valve is attached to one of the fuel delivery pipes, the other one is plugged 85 or capped as at 18^a in the drawing.

85 The valve 19 is provided with a sediment pocket 20, fuel delivery passage 21 and a threaded valve element 22 to close the passage 90 21.

The tank is provided with a filling neck 23, which is closed by a threaded cap 24.

A hood 25 is mounted on an arm 26, which is provided at its end with an opening to receive the neck 23, whereby the arm is pivotally mounted.

The hood 25 may be swung to cover either of the flues.

100 The drip valve may be attached to either of the pipes 17 or 18 and thus either of the

flues may be used as an intake flue while the other flue serves as a discharge chimney.

The intake flue is normally covered by the hood 25, the exhaust chimney being unobstructed so as to allow it to be connected to a chimney pipe or the like.

It is thought to be evident from the foregoing description how the objects hereinbefore set forth are accomplished.

10 The simplicity of construction, strength and cheapness are obtained through the integral tank and brace construction shown.

15 The adaptability of the stove as a brooder stove or a tank heater is derived from the adjustable leg structure, which is fully disclosed in my said patent. The stove may be successfully employed as a brooder stove by raising the stove proper relative to the legs so as to provide a space below the stove, as 20 is essential in brooder stoves for the protection of the chicks and when the stove is to be used as a tank heater, it is immersed in the water of the tank to be heated with the legs adjusted as close to the combustion chamber 25 10 as possible so as to allow the combustion chamber to be positioned as near to the bottom of the tank as possible.

The stove is well fitted for use as a tank heater, due to the imperforate construction 30 of the flues 11 and 12 and the combustion chamber 10. In this regard, I may state that an essential element of the invention involved in the present stove and in the stove disclosed in my said patent is the construction where- 35 by the stove is formed as a tube chamber starting with one of the flues 11 or 12, including the combustion chamber 10 and ending with the other flue. This tube is imperforate from the lower extremity of the com- 40 bustion chamber to a level substantially above the upper extremity of the combustion chamber so that should fuel be fed to the stove faster than it can be burned, the excess fuel will ultimately fill the combustion chamber in 45 such a manner as to cut off all passage of air through the stove. When this occurs, it will be impossible for further burning to occur and the fire will be smothered by the fumes produced in the vertical flues 11 and 12.

50 It is impossible for oil to overflow from the stove until long after the fire has been extinguished. Thus the fire hazard which is a very important problem in connection with all oil burners, particularly of the type em- 55 ployed for brooders, is well coped with in my burner.

Another very important advantage of the integral tank construction resides in the fact that the oil supply tank is kept constantly 60 warm by conduction from the stove. This keeps the fuel in a high fluid state, preventing it from becoming thick and insuring that it will flow freely to the drip valve.

In Fig. 6, I have shown the stove embodied 65 in a brooder. It will be noted that the legs

have been extended so that the stove is raised considerably from the floor, which is indicated by the line 30. A hover 31 is provided, which is supported upon the two flues of the stove.

The exhaust flue is connected to the roof of the building, in which the hover is installed by means of a chimney 32 and the intake flue is connected by the horizontal pipe 33 to a downwardly projecting pipe 34, which terminates very close to the floor 30 so as to suck cold air from the floor. This construction causes a down draft which pulls the heated air from the hover down to the floor and disposes of the cold air at the floor.

70 Some changes may be made in the construction and arrangement of the parts of my invention without departing from the real spirit and purpose of my invention, and it is my intention to cover by my claims, any modified forms of structure or use of mechanical equivalents, which may be reasonably includ- 75 ed within their scope.

80 I claim as my invention:

1. In an oil burning stove, a stove body including upright flues and a winding combustion chamber connecting said flues at their lower ends, and a combined tank and brace united with the flues intermediate their ends, 90 portions of the flues forming end walls of 95 said tank.

2. In an oil burning stove, a stove body including upright flues and a winding combustion chamber connecting said flues at their lower ends, and a combined tank and brace 100 united with the flues intermediate their ends.

3. In an oil burning stove, a stove body including upright flues and a winding combustion chamber connecting said flues at their lower ends, a combined tank and brace united with the flues intermediate their ends, portions of the flues forming end walls of 105 said tank, and a drip valve communicating with the tank through one of said portions.

4. In an oil burning stove, a stove body including upright flues and a combustion chamber connecting said flues at their lower ends and a combined tank and brace united with the flues intermediate their ends, portions of the flues forming end walls of 110 said tank.

5. In an oil burning stove, a stove body including upright flues and a combustion chamber connecting said flues at their lower ends and a combined tank and brace united with the flues near their upper ends, portions of the flues forming end walls of 115 said tank.

6. In an oil burning stove, a stove body including upright flues and a combustion chamber connecting said flues at their lower ends 120 and a combined tank and brace secured to the flues intermediate their ends.

7. In an oil burning stove, a stove body including upright flues and a combustion chamber connecting said flues at their lower ends 125

and a combined tank and brace secured to the flues near their upper ends.

8. In an oil burning stove, a stove body including upright flues and a combustion chamber connecting said flues at their lower ends and a combined tank and brace secured to the flues near their upper ends and a drip valve communicating with the tank and positioned to drip fuel into one of said flues.

10. In an oil burning stove, a stove body including upright flues and a combustion chamber connecting said flues at their lower ends and a combined tank and brace united with the flues intermediate their ends, portions of the flues forming end walls of said tank, and a drip valve communicating with the tank through one of said portions.

10. In an oil burning stove, a stove body including upright flues spaced a substantial distance apart, a tubular combustion chamber connecting said flues at their lower ends and a combined tank and brace secured to the flues intermediate their ends.

11. In an oil burning stove, a stove body including upright flues spaced a substantial distance apart, a tubular combustion chamber connecting said flues at their lower ends and a combined tank and brace secured to the flues near their upper ends.

12. In an oil burning stove, a stove body including upright flues and a combustion chamber connecting said flues at their lower ends, a combined tank and brace secured to the flues near their upper ends, an oil delivery pipe communicating with either end of the tank and terminating at points where they can deliver fuel to the respective flues, means for plugging one of the delivery pipes and a drip valve connected to the other in position to discharge fuel into a flue.

40 Signed this 4th day of June, 1929, in the county of Woodbury and State of Iowa.

CLAUDE SIEBRING.
